(57) **CLAIM**

The ornamental design for the trash can, as shown and described.

DESCRIPTION

FIG. 1 is a front plan view of our trash can;
 FIG. 2 is a rear plan view of the trash can of FIG. 1;
 FIG. 3 is a right side plan view of the trash can of FIG. 1,
 the left side plan view being symmetrical thereto; and,
 FIG. 4 is a top plan view of the trash can of FIG. 1.
 The surface(s) or portion(s) of the article not shown in the
 drawing or described in the specification form(s) no part of
 the claimed design.

1 Claim, 4 Drawing Sheets**FIG. 1**

FIG. 2

FIG. 3

FIG. 4
